UNITED STATES PATENT OFFICE.

ALBERT A. DENSMORE, OF BROOKLINE, MASSACHUSETTS.

ENGINE STARTER.

Application filed February 27, 1923. Serial No. 621,524.

To all whom it may concern:

Be it known that I, ALBERT A. DENSMORE, a citizen of the United States of America, and resident of Brookline, in the county of 5 Norfolk and State of Massachusetts, have invented new and useful Improvements in Engine Starters, of which the following is a specification.

This invention pertains to motor driven starters such as are employed for starting internal combustion engines.

Engine starters of the usual type comprise a motor driven pinion which automatically moves into mesh with a gear connected with the engine shaft and thus drives the latter until the engine starts whereupon the pinion is automatically moved out of mesh with the gear. The operation of the starting motor is controlled by a foot pedal and so long as the pedal is depressed the starting motor continues to run. It frequently happens, by reason of preoccupation or carelessness on the part of the operator, that the pedal is not released immediately after the engine starts and as the motor continues to run the pinion repeatedly approaches the moving gear with the result that the contacting edges of the teeth of the pinion and gear are rapidly worn or broken thus greatly shortening the useful life of the starter device.

The principal object of the present invention is accordingly to provide starter mechanism so constructed and arranged that continued depression of the starter pedal will not result in damage to the teeth of the driving pinion or gear and more particularly to provide starter mechanism with means automatically disconnecting the pinion from the starter motor when the engine starts so that the motor and pinion may rotate independently of each other while the pinion remains in mesh with the engine gear.

45 In the accompanying drawings illustrating the invention:

Fig. 1 is a side elevation, partly broken away and partly in vertical section, showing starter mechanism embodying the present invention, the parts being in their normal or inoperative position;

50 Fig. 2 is a view generally similar to Fig. 1 but showing the parts as positioned for starting the engine;

55 Fig. 3 is a vertical section on the line 3—3 of Fig. 2;

Fig. 4 is a vertical section on the line 4—4 of Fig. 1;

Fig. 5 is a view similar to Fig. 1 but illustrating a modification; and

Fig. 6 is a vertical cross section on the line 6—6 of Fig. 5;

The starter motor is indicated by the numeral 1. This motor is of reversible type and has a shaft 2 whose outer end is journaled in a bearing 3 which may form a part of the engine frame if desired. The operation of the motor is controlled by means of a foot pedal 4 having a stem 5 guided to slide in an opening in the foot board 6 of the vehicle to which the starter mechanism is applied. A spring interposed between the foot board and the pedal normally holds the latter in inoperative position. The stem is furnished with spaced contacts 5^a, 6^a engageable respectively with fixed contacts 5^b, 6^b forming the terminals of conductor wires 7^a, 7^b, respectively leading to the motor. The stem 5 is connected to the motor by means of a conductor wire 7^c. The details of the switch form no part of the present invention, it being only necessary that upon depression of the pedal the contacts 5^a and 5^b first complete the circuit to reverse the motor and upon further depression of the treadle contacts 6^a, 6^b complete the circuit to drive the motor in the forward direction, the reverse operation taking place when the pedal is released.

A hollow cylindrical housing 8 is secured to the motor frame in any desired manner and this housing is furnished at its outer end with a radial rib or flange 9, the housing extending slightly beyond the flange as indicated at 10. A hollow boss 11 projects from one side of the housing concentric with an opening through which a detent pin 12 projects into the housing, the pin being provided with a radial flange. A spring 14 rests upon this flange, the other end of the spring bearing against a cap or cover 13 having threaded engagement with the boss.

A sleeve 15 is secured by means of a pin 16 to the shaft 2. A substantially cylindrical tubular pusher 18 is arranged concentric with the shaft 2, such pusher being internally screw threaded at 19 for engagement with external screw threads 17 upon the sleeve 15. The exterior surface of this pusher is provided with a plurality of longitudinally extending grooves or slots 20 for cooper-

tion with the detent pin 12, normally to prevent rotation of the pusher with the shaft. The outer end of the pusher is provided with a plurality of lugs or projections 21 constituting clutch elements cooperative with shallow radial grooves 22 in a flange 23 projecting radially from the hub 24 of a pinion 25. The pinion 25 with its hub is free to turn and slide on the shaft 2. The end of the hub 24 is furnished with a second radial flange 26 spaced from the flange 23 to provide an elongate circumferentially extending groove for the reception of an annular inwardly directed flange 27 at the outer end of the pusher. A spring 28 is interposed between the flange 23 of the pinion and the flange 9 of the housing and this spring normally tends to separate the pusher and pinion so as to take up lost motion 20 between them and to prevent rattling.

The numeral 29 indicates an engine gear with which the pinion 25 may be caused to mesh by moving it axially along the shaft. The term "engine gear" is herein employed 25 as a convenient expression for designating any gear, whether mounted directly upon the engine shaft or not, which turns synchronously with the engine shaft and by means of which power may be transmitted to the latter. To facilitate entrance of the teeth of the pinion 25 into the spaces between the teeth of the gear 29, the ends of the teeth of the pinion may be beveled as indicated at 30. A stop collar 31 is secured to the shaft 35 2 at a suitable point to limit movement of the pinion 25 and likewise to limit excess axial movement of the pusher.

The operation of the parts just described is substantially as follows, it being assumed 40 that they normally occupy the position shown in Fig. 1. Upon depression of the pedal 4 contacts 5^a and 5^b are engaged, thus reversing the motor and driving the shaft in a direction which would tend to retract the pusher into the housing. As the pusher can at this time move no further in this direction the detent pin 12 snaps out of the slot 20 with which it may engage and the pusher rotates with the shaft and sleeve. 45 This action, however, is but momentary as the continued depression of the treadle immediately breaks contact of the parts 5^a and 5^b and then brings the contacts 6^a and 6^b into engagement. As the pedal is now held 50 in depressed condition the motor changes its direction and the rotation of sleeve 15 causes the pusher to advance outwardly from the housing, the detent pin holding the pusher against rotation of the shaft.

60 During the early stages of this movement the spring 28 pushes the pinion 25 to the right as viewed in Fig. 1, and this movement may continue until the pinion 25 has been moved into mesh with the gear 29. Whether 65 or not the pinion is moved fully into mesh

with the gear 29 by the action of the spring 28, the pusher will continue its movement until the lugs or projections 21 engage grooves 22 of the flange 23 whereupon, if the movement of the pinion has not been completed, it will be positively moved until it engages the stop member 31. As axial movement of the pinion 25 and of the pusher is thus limited, the pusher is constrained to partake of the rotation of the shaft 2, the 70 detent 12 snapping successively from one of the slots 20 to another. The cooperating clutch elements 21 and 22 now transmit movement of rotation from the pusher to the pinion 25 and thus drive the gear 29 until 75 the engine starts. As soon as the engine picks up speed and tends to drive the pinion 25 at a greater rate than that imparted by the motor 1, the pusher backs off slightly by the action of the screw threads 17, 19 80 until the clutch elements are disengaged, the elongate groove in the hub of the pinion permitting such movement. The pinion now remains in mesh with the gear 29, being driven by the latter, while the shaft 2 may 85 continue to rotate so long as the pedal is depressed. If the pedal is not immediately released the pusher may again advance toward the rotating flange 23, but upon coming into contact with the latter will immediately withdraw again and as the projections 21 and the grooves 22 are provided with rounded edges, no particular harm is done by repeated engagement of the parts. The clutch elements shown may in many 90 instances be replaced advantageously by friction surfaces of any desired material, as hereinafter more fully described. When the foot pedal is released the motor stops and is then reversed for a short interval during 95 which the pusher is retracted and thus positively withdraws the pinion 25 from the gear 29, thus restoring the parts to the position shown in Fig. 1. As the foot pedal resumes 100 its normal position the contacts 5^a and 5^b 110 are disengaged and the motor comes to rest.

In Figs. 5 and 6 a modified form of the device is illustrated which in general is similar to that above described, but differs in the employment of a pinion 35 having a bore 115 of a diameter substantially larger than that of the shaft 2, so that in normal position the pinion is eccentric to the shaft. Preferably, to assist in holding the pinion in its normal position, a spring 37 of any desired type is 120 interposed between the shaft and the interior surface of the hub 34 of the pinion, such spring being seated in a groove in the latter surface, if desired. In this instance the stop member 41 corresponding to the stop 31 of the previous modification is provided with a sleeve portion 42 concentric with the shaft and terminating in a beveled end. Preferably also in place of the spring 28 of Fig. 1, a washer 43 is arranged con- 125 130

centrically with the shaft and bearing against the inner end of the hub 34 of the pinion 35, and a spring 44 of any desired type bears against this washer and against the interior shoulder 45 of the pusher, such spring serving to prevent rattling of the parts in the same manner as the spring 28 above described. The projections of the pusher are here replaced by a friction washer 43^a while the grooves of the flange 23 are omitted, the surface of the flange being roughened or not as may be desired.

When the pusher is advanced by the motor 1, the pinion 35 rides up on the bevel surface 43 of the sleeve 42 until it bears upon the sleeve 42. In this position the pinion meshes with the gear 29 and the washer 43^a frictionally engages flange 23, the operation of the parts being substantially like that previously described. When, however, the pinion is retracted it moves down off of the sleeve 42 into the position shown in Fig. 5, where it comes to rest.

I claim:

1. An engine starter comprising in combination with an engine gear, a pinion for driving the latter, a reversible motor, and means actuated by the motor, when turning in one direction, for advancing the pinion into mesh with the engine gear and for rotating the pinion to drive the gear, and when turning in the opposite direction, for disengaging the pinion from the gear.

2. Engine starter mechanism comprising a reversible motor having a shaft, a pinion, and means operative upon rotation of the motor shaft in one direction to advance the pinion into mesh with an engine gear and to clutch the pinion to the shaft to transmit motion to the engine gear, the clutch becoming inoperative upon starting of the engine, and the pinion being moved out of mesh with the engine gear only upon reversal of the motor.

3. Engine starter mechanism comprising in combination with an engine gear, a pinion movable into and out of mesh with the gear, a reversible motor, and means operative upon turning of the motor in one direction to advance the pinion into mesh with the gear and to rotate the pinion to drive the gear, the pinion being automatically disconnected from the shaft while remaining in mesh with the gear after the engine starts, the parts being so constructed and arranged that the pinion is moved out of mesh with the gear only upon reversal of the motor.

4. Engine starter mechanism comprising in combination with an engine gear a rotary shaft, a normally eccentric pinion free to turn relatively to the shaft, actuating means for moving the pinion axially to cause it to mesh with the engine gear and for centering the pinion relatively to the drive shaft,

and clutch means for transmitting motion from the shaft to the pinion when the latter is meshed with the engine gear.

5. Engine starter mechanism comprising in combination with an engine gear, a drive shaft, a pinion provided with an elongated hub having an elongated circumferential groove therein and being free to turn and slide upon the shaft, a pusher movable axially of the shaft, said pusher having an annular flange engaging the elongate circumferential groove in the hub of the pinion, spring means normally tending to maintain said flange at one end of the groove, and means for moving the pusher axially to advance the pinion into mesh with the engine gear.

6. Engine starter mechanism comprising a motor having a shaft, a pinion turning and sliding freely on the shaft, said pinion having an elongate hub terminating at opposite ends in radial flanges, an element carried by the shaft, a pusher having threaded engagement with said element and provided with a radial flange interposed between the flanges of the pinion hub, a fixed housing concentric with the shaft, a detent supported by the housing, said detent being normally operative to prevent turning of the pusher, and a spring interposed between the housing and one of the flanges of the hub and tending to separate the pusher and pinion.

7. Engine starter mechanism comprising a drive shaft having a pinion free to turn and slide thereon, the bore in the pinion being of substantially greater diameter than that of the shaft, a sleeve fixedly secured to the shaft having a beveled end engageable with the pinion for raising the pinion and centering it as it is moved axially of the shaft, an element carried by the shaft, and a pusher having screw threaded engagement with said element and operative to advance the gear onto the sleeve fixed to the shaft when the shaft is rotated.

8. Engine starter mechanism comprising a motor driven shaft, a pinion turning and sliding freely on the shaft, said pinion having a bore of a diameter larger than that of the shaft, a spring interposed between the pinion and shaft normally maintaining the pinion eccentric to the shaft, a pusher operable upon turning of the shaft for advancing the pinion in an axial direction, and means for centering the pinion relatively to the axis of the shaft during its advancing movement.

9. Engine starter mechanism comprising in combination with an engine gear, a motor having a shaft, a normally eccentric pinion free to turn and slide axially relatively to the shaft, means operating when the shaft is rotated for centering the pinion relatively to the drive shaft and moving the pinion into

- driving engagement with the engine gear, and means, including a clutch, for transmitting movement of rotation from the shaft to the pinion to drive the engine gear, 5 said clutch comprising cooperable elements, and means connecting said elements providing for limited relative axial movement thereof.
10. Engine starter mechanism comprising 10 in combination with an engine gear, a rotary and axially movable pinion engageable with the engine gear for driving the latter, means for moving the pinion into mesh with the gear and for positively retracting the pinion 15 from the engine gear, said means comprising disengageable clutch elements for rotating the pinion to drive the gear, the clutch elements being automatically disengaged when the engine starts.
11. Engine starter mechanism comprising 20 in combination with an engine gear, a drive shaft, a pinion free to turn and slide on the shaft, said pinion having an elongate hub provided with a radial flange, a pusher 25 having screw-threaded engagement with an element of the shaft, a spring pressed member normally operative to prevent rotation of the pusher with the shaft whereby upon 30 rotation of the shaft the pusher is constrained to move axially and advance the pinion into mesh with the engine gear, cooperable clutch elements for connecting the pusher and pinion, one of said clutch elements being carried by the pusher, said element 35 being disposed between the other clutch element, carried by the pinion, and the flange upon the hub of the pinion, and a stop collar on the shaft to limit axial movement of the pinion and pusher.
12. Engine starter mechanism comprising, 40 in combination with an engine gear, a motor having a shaft, an externally screw-threaded sleeve fixed to the shaft, a normally eccentric pinion free to turn and slide on the shaft, a pusher having threaded engagement with the sleeve, a spring pressed pin normally operative to prevent rotation of the pusher so that the latter moves axially when the shaft is rotated to advance the pinion into mesh with the engine gear, means to center the pinion relatively to the shaft as it advances toward the engine gear, engageable clutch elements carried by the pinion and pusher respectively, and a stop collar 45 on the shaft to limit axial movement of the pinion and pusher.
13. Engine starter mechanism comprising in combination with an engine gear, a motor having a shaft, a normally eccentric pinion free to turn and slide on the shaft, a screw-threaded sleeve fixed to the shaft, a tubular pusher having threaded engagement with the sleeve, a spring pressed detent normally engaging a longitudinally extending element of the pusher to prevent rotation of the latter whereby upon rotation of the motor shaft the pusher moves axially to advance the pinion into mesh with the engine gear, means to center the pinion relatively to the shaft, and a stop to limit axial movement of the pinion and pusher. 50
14. Engine starter mechanism comprising in combination with an engine gear, a drive shaft, a screw threaded member carried thereby, a pinion turning and sliding freely 55 on the shaft, said pinion having an elongate hub provided with spaced radial flanges, a tubular substantially cylindrical pusher having screw threaded engagement with the threaded member upon the shaft and having an element disposed between the spaced flanges of the hub, said pusher being provided with a plurality of circumferentially spaced, longitudinally extending slots in its outer surface, a spring pressed detent pin 60 normally engaging one of said slots to prevent rotation of the pusher, whereby upon rotation of the shaft the pusher is moved axially to advance the pinion into mesh with the engine gear, and a stop for limiting such axial movement. 65
15. Engine starter mechanism comprising in combination with an engine gear, a motor having a drive shaft, a normally eccentric axially movable pinion free to turn upon the 70 drive shaft, a clutch element carried by the pinion, a cooperating clutch element movable with the drive shaft, cooperable members carried by the respective clutch elements to limit relative motion thereof, and means for moving the drive shaft clutch element axially to push the pinion into mesh with the engine gear, and to center the pinion relatively to its shaft as it advances toward the gear. 75

- ALBERT A. DENSMORE.

- driving engagement with the engine gear, and means, including a clutch, for transmitting movement of rotation from the shaft to the pinion to drive the engine gear, 5 said clutch comprising cooperable elements, and means connecting said elements providing for limited relative axial movement thereof.
10. Engine starter mechanism comprising in combination with an engine gear, a rotary and axially movable pinion engageable with the engine gear for driving the latter, means for moving the pinion into mesh with the gear and for positively retracting the pinion 15 from the engine gear, said means comprising disengageable clutch elements for rotating the pinion to drive the gear, the clutch elements being automatically disengaged when the engine starts.
11. Engine starter mechanism comprising in combination with an engine gear, a drive shaft, a pinion free to turn and slide on the shaft, said pinion having an elongate hub provided with a radial flange, a pusher 25 having screw-threaded engagement with an element of the shaft, a spring pressed member normally operative to prevent rotation of the pusher with the shaft whereby upon rotation of the shaft the pusher is constrained to move axially and advance the pinion into mesh with the engine gear, cooperable clutch elements for connecting the pusher and pinion, one of said clutch elements being carried by the pusher, said element being disposed between the other clutch element, carried by the pinion, and the flange upon the hub of the pinion, and a stop collar on the shaft to limit axial movement of the pinion and pusher.
12. Engine starter mechanism comprising, in combination with an engine gear, a motor having a shaft, an externally screw-threaded sleeve fixed to the shaft, a normally eccentric pinion free to turn and slide on the shaft, a pusher having threaded engagement with the sleeve, a spring pressed pin normally operative to prevent rotation of the pusher so that the latter moves axially when the shaft is rotated to advance the pinion into mesh with the engine gear, means to center the pinion relatively to the shaft as it advances toward the engine gear, engageable clutch elements carried by the pinion and pusher respectively, and a stop collar
- on the shaft to limit axial movement of the pinion and pusher.
13. Engine starter mechanism comprising in combination with an engine gear, a motor having a shaft, a normally eccentric pinion free to turn and slide on the shaft, a screw-threaded sleeve fixed to the shaft, a tubular pusher having threaded engagement with the sleeve, a spring pressed detent normally engaging a longitudinally extending element of the pusher to prevent rotation of the latter whereby upon rotation of the motor shaft the pusher moves axially to advance the pinion into mesh with the engine gear, means to center the pinion relatively to the shaft, and a stop to limit axial movement of the pinion and pusher.
14. Engine starter mechanism comprising in combination with an engine gear, a drive shaft, a screw threaded member carried thereby, a pinion turning and sliding freely on the shaft, said pinion having an elongate hub provided with spaced radial flanges, a tubular substantially cylindrical pusher having screw threaded engagement with the threaded member upon the shaft and having an element disposed between the spaced flanges of the hub, said pusher being provided with a plurality of circumferentially spaced, longitudinally extending slots in its outer surface, a spring pressed detent pin normally engaging one of said slots to prevent rotation of the pusher, whereby upon rotation of the shaft the pusher is moved axially to advance the pinion into mesh with the engine gear, and a stop for limiting such axial movement.
15. Engine starter mechanism comprising in combination with an engine gear, a motor having a drive shaft, a normally eccentric axially movable pinion free to turn upon the drive shaft, a clutch element carried by the pinion, a cooperating clutch element movable with the drive shaft, cooperable members carried by the respective clutch elements to limit relative motion thereof, and means for moving the drive shaft clutch element axially to push the pinion into mesh with the engine gear, and to center the pinion relatively to its shaft as it advances toward the gear.
